CLAIM

The ornamental designs for a solar-powered illumination device, as shown and described.

DESCRIPTION

FIG. 1 is a front perspective view of a solar-powered illumination device;

FIG. 2 is an alternate perspective view of FIG. 1;

FIG. 3 is an exploded view of FIG. 1;

FIG. 4 is a top view of FIG. 1;

FIG. 5 is a side view of FIG. 1;

FIG. 6 is a bottom view of FIG. 1;

FIG. 7 is an end view of FIG. 1; and,

FIG. 8 is an opposite end view of FIG. 7.

The broken lines used in FIGS. 1, 2, and 6 of the drawings disclosure are for illustrative purposes only and form no part of the claimed design.

1 Claim, 4 Drawing Sheets
